UNITED STATES PATENT OFFICE.

BOSCOE CLYDE MALCOM, OF WICHITA, KANSAS.

THERMAL SWITCH.

Application filed May 10, 1926. Serial No. 108,137.

- This invention relates to thermal switches and has for its object the provision of a novel thermometer operated circuit closer adapted for use for a wide variety of purposes for closing the circuit through signal devices, alarms or any other electrically operated indicating or control means, the device acting in accordance with temperature variations.
- 10 An important and more specific object is the provision of a circuit closer embodying a column of mercury or other similar conducting material adapted to rise under the expansive influence of heat and adapted to engage against a succession of contacts whereby a circuit or circuits to signal or control devices may be controlled in accordance with temperature variations.
- 15 Another object of the invention is to provide a device of this character embodying a contact device longitudinally movable with respect to a thermometer tube and adapted to be engaged with a selected one of a series of contacts entering the same in position to be engaged by the column of mercury when the same rises under the influence of heat.
- 20 An additional object is to provide a thermal circuit closer of the character described which will be simple and inexpensive in manufacture, easy to use, positive in action, efficient and durable in service, and a general improvement in the art.
- 25 With the above and other objects and advantages in view, the invention consists in the details of construction and the arrangement and combination of elements to be hereinafter more fully described and claimed, and illustrated in the accompanying drawings, in which:—
- 30 Figure 1 is a front elevation of the complete device.
- 35 Figure 2 is a longitudinal section taken on the line 2—2 of Figure 1, and
- 40 Figure 3 is a detail cross section taken on the line 3—3 of Figure 1.
- 45 Referring more particularly to the drawings, I have shown the device as comprising a base 10 preferably of insulating material and having mounted thereon a thermometer device including a bulb 11 preferably having a protective covering 12 of rubber or other insulating material, the thermometer device further including an elongated constricted cylindrical tube 13 which extends upwardly along the base and which has extending thereinto at spaced points, a plurality of metallic contact elements 14 which will of course be engaged by the column of mercury 15 within the thermometer device, when the column rises under the influence of heat.
- 50 It is of course clear that any suitable means may be provided for mounting the thermometer device upon the base, but in the present instance, I have illustrated a clip or bracket device 16 which embracingly engages the covering 12 and which is secured to the base. Obviously, the base may be provided with holes 17 or any other equivalent means whereby securing elements may be utilized for effecting securing upon a stationary support, such details being entirely immaterial in so far as the scope of the invention is concerned. It is also preferable to provide a bracket device 18 mounted upon the base and embracingly engaging the cylindrical tube portion 13 of the thermometer structure for securing the same and preventing displacement of any of the parts.
- 55 Extending into the bulb 11 at the lower portion thereof is a contact or wire or other conductor 19 which, of course, makes electrical contact with the mass of mercury located within the tube and bulb. Any desired means may be provided connected with this wire though in the present instance, the connection is simply disclosed as being an insulated wire, the insulated portion 20 thereof being located within a depending flange portion 21 of the protective covering, the bare wire itself being sealed into the bulb as clearly indicated.
- 60 Mounted upon the base 10 at a point near the upper end of the thermometer tube 13 is a metallic bracket member 22 which is here shown as secured to the base and adapted to be contracted by means of a nut member 23 engaged upon a threaded post 24. As a matter of fact, the threaded post may constitute the entire securing means for the bracket device in addition to acting as a means for effecting adjustment of the bracket.
- 65 Slidably mounted within the bracket device 22 is a tubular covering 25 of insulating material within which is located a metallic tubular shell 26 slidably engaged upon the thermometer tube 13 and adapted to be brought into engagement with a selected one of the contacts 14 extending thereinto. The metallic member 26 terminates in a plug or head 27 carrying a securing screw or the like.

28 with which is connected one end of a conductor 29. Obviously, when the mercury 15 within the bulb and tube rises and engages any one of the contacts 14, and this contact 14 is engaged by the metallic member 28, the circuit will be closed to whatever device is connected with the apparatus.

As a matter of fact, it may be preferable to provide a series of graduations or indications 30 upon the base adjacent the various contact members 14 which extend into the thermometer tube, these various indications designating degrees of temperature.

In the operation of the device, let it be assumed that it is desired to set the mechanism so that the circuit will be closed when the temperature rises to 440 degrees. In such a case, the nut member 23 is loosened so as to permit the assembled members 25 and 26 to be slid through the bracket device 22 so as to engage the contact member 14 opposite the graduation 440. When this is done, it is quite apparent that there is nothing more necessary inasmuch as if the temperature rises to this degree, the expansion of the mercury 15 within the bulb and tube will cause the mercury column to come into engagement with the contact 14 which is opposite the graduation 440. When this is done, it is obvious that there will be nothing whatsoever to obstruct the flow of current through the device and through whatever alarm, signal or control mechanism is utilized in connection therewith. It is really believed that the construction, operation and advantages will be readily apparent to one skilled in the art without further explanation.

While I have shown and described the preferred embodiment of the invention, it should be understood that I reserve the right to make such changes in the form, construction and arrangement of parts as will not depart from the spirit of the invention or the scope of the subjoined claims.

Having thus described the invention, I claim:

1. In a thermal circuit closer, a tube and bulb containing mercury and providing a

thermometer, a protective covering of insulating material for said bulb and adjacent portion of said tube, a flange formed on said protective covering, a conductor sealed into the thermometer and having electrical connection with the mercury therein at all times, said conductor having an insulated portion received in said flange, a plurality of contacts sealed into the tube and adapted to have contact with the mercury therein when the latter rises under the influence of heat, a conducting member adapted to be brought into engagement with a selected one of said last mentioned contacts, said conducting member consisting of a headed cylindrical metallic shell slidably mounted about the tube, a supporting bracket, a covering of insulating material for the shell member and being slidably arranged within said supporting bracket, and a conductor fixed to said head.

2. In a thermal circuit closer, a tube and a bulb containing mercury and providing a thermometer, a protective covering of insulating material for said bulb and adjacent portion of said tube, a flange formed on said protective covering, a conductor having an insulated portion received in said flange, said conductor being sealed into the thermometer and having electrical connection with the mercury therein at all times, contact means sealed into the tube and adapted to have contact with the mercury therein when the latter rises under the influence of heat, a conducting member adapted to be brought into engagement with said contact means, said conducting member consisting of a cylindrical metallic shell member slidably mounted about the tube, a supporting bracket, a covering of insulating material for the shell member, said covering carrying the shell member, means included in said supporting bracket for engagement with the covering and for clamping the shell member with the contact means, and a conductor fixed to said shell member.

In testimony whereof I affix my signature.

ROSCOE CLYDE MALCOM.
